POWER HEAD ARROW

Leo J. West, 105.6 Mile Road, Comstock Park, Mich.

Filed Aug. 1, 1958, Ser. No. 752,651

1 Claim. (Cl. 273—106.5)

This invention relates generally to archery. More particularly, the invention has reference to an arrow the head of which has means for driving the same more deeply into the game than would normally be the case.

One object of importance is to provide an arrow head which will make a clean, fast kill on impact with the game, by reason of an arrangement wherein gun powder caps in back of the arrow head will drive the same more deeply into the flesh of the animal.

Another object is to provide an arrow head which will have a means for driving the same more deeply into the game, which means will respond to the impact of the arrow head against the animal.

Still another object is to provide, for use in association with the sharply tipped arrow head that is employed to kill the game, a second type of arrow head which will be rounded, and which will be used to shoot over and beyond the game in a way such that on impact, it will create a noise that will tend to drive the game more closely to the hunter, within an effective range.

Another object is to provide an arrow head which will be so designed as to permit light poundage bows to be used, in a manner such that the penetration of the arrow into the game will be as great as that which would result when the more usual heavy poundage hunting bow is employed. In this way it is proposed to permit hunters having less strength than that normally required for heavy poundage bows, to have the same opportunities in hunting game with bow and arrow as that which is now reserved only for hunters having greater strength and the capability of using heavier bows.

Another object is to so design the arrow head that on impact, the head will be driven more deeply into the game but the shaft of the arrow will be caused to be completely or at least partially moved rearwardly, to be ejected from the flesh of the animal so as to facilitate its being retrieved and reused.

Still another object is to provide a device of the character stated that will be designed to prevent an arrow from being impaled within a tree under conditions such that retrieving of the arrow would be eliminated, the device being adapted to cause the shaft to be ejected if the arrow should strike a tree, and to drop to the ground.

Another object is to provide an arrow as stated which will permit the same to be used either as a hunting arrow with a power head or as a target arrow without the head, by reason of the fact that the shaft can receive either type of head.

Another object is to provide an arrow which will be designed to resist breakage, to an extent above and beyond the resistance that is characteristic of an ordinary arrow.

Other objects will appear from the following description, the claim appended thereto, and from the annexed drawing, in which like reference characters designate like parts throughout the several views, and wherein:

Figure 1 is a view of an arrow according to the present invention, partially in side elevation and partially in lon-

2

gitudinal section, a portion of the shaft being broken away;

Figure 2 is a fragmentary elevational view of the arrow at the juncture of the head and shaft;

5 Figure 3 is an elevational view on a reduced scale, portions being broken away, showing the device in use;

Figure 4 is a fragmentary view of a modification, partly in elevation and partly in section;

10 Figure 5 is an exploded perspective view of the modified form shown in Figure 4, illustrating the arrow head of the form of Figure 4; and

Figure 6 is a fragmentary perspective view of the shaft used in the form of the invention shown in Figures 1 and 4.

Referring to the drawing in detail, designated generally at 10 is an arrow according to the present invention. This includes a shaft 12 having the usual tail feathers 14 and nock 16.

20 At the forward end of the shaft 12 there is provided a cylindrical, cup-shaped, metal ferrule 18. This is of elongated formation, and the front end of the body portion of the shaft is reduced slightly to receive the ferrule, as shown at 19. Therefore, the outer surface of the ferrule is flush with the outer surface of the body portion 21 of the shaft 12.

Designated at 22 is a plurality of explosive caps. These are of the same variety as used in children's cap pistols. Such caps are of flat formation, and are essentially provided with pockets in which the explosive powder is confined. The caps explode on impact, as is well known.

30 Caps 22 are disposed within a cylindrical base 20 of the arrow head 24. In the form shown in Figures 1-3, the arrow head is of sharp formation, and by reason of this arrangement is adapted to penetrate the game. This particular shape of arrow head is, of course, somewhat akin to that which is conventional in hunting arrow heads. In accordance with the invention, however, the metal, tapered body 25 of the arrow head is integral with the cylindrical, constant diameter base 20 the inner diameter of which is adapted to slidably receive the ferrule 18 in the manner shown in Figure 1. The caps are held within the base 20, the base opening rearwardly to receive the ferrule. Base 20, at its forward end, is integrally connected to the rear end surface 27 of the body 40 25 of the arrow head.

45 It will be observed that the arrangement is such that should the arrow head strike an object, it would tend to move rearwardly relative to the shaft, that is, the shaft would continue its forward movement even though the forward movement of the arrow head is abruptly brought entirely, or almost entirely, to a halt. Therefore, the caps will be exploded, and the gas created by the explosion cannot move rearwardly due to the closing of the rear end of the base 20 by the ferrule. Therefore, the arrow head will be forcibly driven forwardly relative to the shaft, deeper into the flesh of the animal A in the manner shown in Figure 3. A concurrent result is that the shaft will be forcibly impelled rearwardly out of the animal, to drop to the ground so that it can be reused.

50 By reason of this arrangement, it is obvious that a bow can be used that is of lighter poundage than that ordinarily required, at a particular, given range for both light and heavy poundages. In other words, if one were shooting the game from a distance of perhaps 50 yds., ordinarily 55 a heavier poundage bow such as a 50 lb. bow would be required, to cause the arrow to penetrate the game sufficiently to kill the same. The arrow head of the invention would permit one to use a 25 lb. bow at the same range, in a manner such that even though the impact of the arrow against the game would be lighter, the explosion of the caps would drive the arrow head immediately into the

game, sufficiently to kill the same quickly and cleanly. This permits hunting with bow and arrow to be employed by persons who ordinarily have had to refrain from indulging in this sport, due to inability to use heavy hunting bows.

Further, the arrow can be of very light formation, since there is no fine mechanism or springs, thereby facilitating its employment in hunting with bow and arrow. Further, the arrow tends to avoid breakage, resisting breakage to an extent far more than the ordinary arrow.

If the arrow should strike a tree or the like, an ordinary arrow tends to become impaled in the tree to an extent such that its retrieving is impossible. The present invention, however, causes the shaft to be ejected rearwardly and dropped to the ground for reuse.

Referring to Figures 4 and 5, a modification is here shown in which the same shaft is used. The arrow head 30 is of globular formation, however, and integrally connected to its rear end surface 35 is a base 32 similar to the base 20.

This form of the invention is used in situations in which the deer or other game is too far away for a good shot. By shooting over the deer, the arrow will strike an object, and the caps will explode on the other side of the deer, in a manner such that the noise will drive the deer closer to the hunter so that he may have a good shot.

The principle, of course, remains unchanged.

It will be apparent that the invention possesses many advantages not true of power heads previously devised for arrows. Lightness is a characteristic of the invention, and low cost is also a characteristic. The adaptability for retrieving the shanks of the arrows is also present, and also the adaptability of insuring maximum penetration of the game despite relatively light weight bows that are being employed.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor change in construction that may be permitted within the scope of the appended claim.

What is claimed is:

An arrow including an elongated shaft having a leading

end and a trailing end, said shaft at its trailing end being formed with an arrow nock, the shaft including a plurality of tail feathers immediately forward of said nock, the shaft being formed at its leading end with a portion reduced in diameter in respect to the remaining portion of the shaft, said remaining portion of the shaft being constant in diameter fully from the juncture thereof with the reduced portion, to the trailing extremity of the shaft, said reduced portion being of constant diameter from end-to-end thereof; a cylindrical cup-shaped, metal ferrule on the reduced portion of the shaft, said ferrule extending the full length of said reduced portion with the outer surface of the ferrule being flush with the outer surface of said remaining portion of the shaft over the full length of the ferrule whereby said shaft, over the full distance between its leading and trailing extremities, will be of constant external diameter, the ferrule having a wholly closed leading end overlying the leading end of said reduced portion of the shaft; an arrowhead including a metallic body at its leading end, and a cylindrical, constant diameter base integral with said body and projecting rearwardly therefrom, said base having an axial recess the inner diameter of which is constant over the full length thereof and substantially matches the external diameter of the ferrule, thus to snugly, slidably receive the ferrule, said ferrule and recess being substantially co-extensive in length, the outer diameter of said base being constant from end-to-end thereof and being slightly greater than the diameter of the shaft, the recess being formed with a flat inner end surface disposed in a plane perpendicular to the length of the base, said closed end of the ferrule being flat and being disposed in a plane parallel to the plane of said inner end of the recess whereby the inner end surface of the recess and said closed end of the ferrule constitute an anvil and hammer respectively; and a plurality of superposed percussion-type explosive caps interposed between the anvil and hammer in said recess so as to be detonated responsive to forcible direction of the arrowhead against an object.
